UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

HEMMING ATTACHMENT FOR SEWING MACHINES.

Application filed October 29, 1913. Serial No. 797,946.

To all whom it may concern:

Be it known that I, ALBERT H. DE VOE, a citizen of the United States, residing at Westfield, in the county of Union and State 5 of New Jersey, have invented certain new and useful Improvements in Hemming Attachments for Sewing Machines, of which the following is a specification, reference being had therein to the accompanying 10 drawings.

This invention has for its object to provide a hemming attachment especially adapted for hemming endless circular pieces of work such as the bottoms of knit under- 15 shirts and the like more specifically it is desirable to enable a circular hem to be completed with as little manipulation as possible by the operator, dispensing with the necessity for bodily retraction of the entire hem- 20 mer or for removal of goods from the hem- mer and subsequent hand directed stitching.

The attachment comprises a base member formed with an edge-turning curved wall and provided on its lower face with guide- 25 ribs to engage a primary folding member, the latter being adjustably secured to the base member by means of a thumb-screw. The primary folding member is formed with an upwardly turned guide-wall provided 30 with an overhanging lip. The upper face of the base member is provided with a channel to receive a grooved block depending from a guide-plate having a lip which normally overhangs the hem cavity. The 35 guide-plate may be retracted to one side of the hem cavity—its depending block sliding within the aforesaid channel of the base member for this purpose. The base member is provided with a spring-pressed pin which 40 is adapted to enter the groove formed in the guide-block to prevent upward movement of the guide-plate. The travel of the guide-plate is confined within certain limits by suitable stops.

45 The base member is rigidly connected to a supporting post which in the present instance is shown secured to the end of a sewing machine cylinder-arm but it is obvious that the hemmer may be arranged at the side 50 of the bed-plate for feeding across the arm where the nature of the work to be done would be facilitated by such arrangement, as for instance in completing the circular

hem on small tubular work such as sleeves, trousers and the like. The edge-turning wall 55 of the base member projects beyond the body of said member and is adapted to enter a slot formed in the throat-plate supported by said cylinder-arm and to extend above said throat-plate slightly to one side of the 60 line of seam. The primary folding member is provided with a projecting U-shaped guide tongue which overhangs the cylinder-arm and coacts with the projecting wall of the base member in guiding the hem to a point 65 within the field of action of the feed-dog.

The invention will be understood by reference to the accompanying drawings, in which Fig. 1 is a perspective view of a sewing machine provided with the present improve- 70 ments. Fig. 2 is a sectional view of the hemmer on line *a*—*a* Fig. 1. Fig. 3 is a sectional view of the hemmer on line *b*—*b* Fig. 1, and Figs. 4, 5, 6 and 7 are detail views of the component parts of the hemmer.

75 The hemmer is shown herein applied to the bed-plate of a cylindrical feed-up-the-arm machine. The machine is provided with the usual cylindrical end-cap 1 and removable throat-plate 2 having openings for 80 the passage of the needles 3 and the feed-dog 4. The end of the cap 1 is provided with the channel 5 to receive the supporting post 6 of the attachment, the latter being secured to the cap by means of a screw 7 85 which passes through a slot 8 formed in the post. The base member 9 is secured to the post 6 by means of screws 10 which pass through slots 8^x formed in the post and enter threaded apertures formed in the base mem- 90 ber. The slots 8 and 8^x with which the post 6 is provided permit bodily adjustment of the hemmer relatively to the throat-plate 2.

95 The base member 9 is formed with an inner curved edge-turning wall 9^x and is provided with depending guide-ribs 11 and 12 adapted to engage respectively the side edge 13 of a primary folding member 14 and the walls of slot 15 formed in said member. The primary folding member 14 or outer folding 100 portion of the hemmer is adjustably secured to the base member 9 by means of a set-screw 16 which enters the slot 17 of said primary member.

The primary member is formed with an 105 upwardly turned guide-wall 14^x provided

with an overhanging flange 18, which lies slightly above the horizontal plane of a guide-plate 19 provided with a longitudinally grooved depending block 19^x. The 5 body portion of the guide-plate is supported by the base member 9, its block 19^x being adapted to slide within a channel 21 formed in said base member. This guide-plate has a marginal portion adjacent the flange 18 10 overhanging the edge-turning wall 9^x and affording a work-engaging lip which is readily retractable. Upward movement of the guide-plate is prevented by means of a 15 detent-pin 23 fitted within socket 22 of the base member and pressed outwardly by spring 24 into engagement with depressions 23^x in a groove 20 formed in block 19^x. The guide-plate is adapted to be moved to one side thereby opening the top of the hem 20 cavity and permitting the stitching operation to be continued uninterruptedly up to the initial sewing point. This retractive movement is obtained either by the operator engaging a recess 19' in the plate with his 25 thumb or finger or by the initially formed stitching engaging the inclined front edge 19" on the guide-plate 19 at the receiving end of the hemmer, the pull of the feed on the fabric acting with sufficient force on the 30 inclined edge 19" to displace the guide-plate against the light yielding pressure of spring-pressed detent pin 23. The guide-plate 19 is provided with a depending lug 25 and with a projecting tongue 29 which engage 35 respectively the outer wall of base member 9 and shoulder 26 provided at the upper edge of post 6 whereby the movement of plate 19 toward and from the overhanging flange 18 of the primary folding member is limited. 40 The bearing support, whereby the lip or plate 19 may be retracted, is afforded by the upper surface of the base member 9 and the walls of the channel 21 which fixed supporting or bearing surfaces are external to the 45 hem-cavity or space embraced between the outer and inner guide-walls and hence permit the lip 19 to be shifted to a position removed from the hem-cavity.

In conjunction with each other the primary folding member 14 and the edge-turning wall of base member 9 form a hem cavity, the width of which is determined by the 50 adjustment of said primary member upon the base member. The guide-plate 19 having a lip is adapted to normally overhang the hem cavity, partially closing the same and serving to support the work and to cooperate with the edge-turning wall 9^x in guiding the edge of the work. The primary folding member is provided with a projecting U-shaped guide-tongue 27 which cooperates with the projecting portion 28 of the edge-turning wall of base member 9 in guiding the hem within the range of action of the 55 feed-dog, the said projecting members being

adapted to overhang the throat-plate of the machine at opposite sides of the line of seam. The base member 9 and guide-plate 19 constitute an inner folding member over which the fabric is adapted to pass.

In the operation of the attachment the edge of the fabric *f* is brought over the face of the guide-plate 19 and under the overhanging flange 18 of the primary folding member, thence into engagement with the 70 curved turning wall of the base member 9 which guides the edge back toward the overhanging flange 18 and thereby forms the hem, the position of the fabric being shown in Fig. 2. The lower face of the base member 9 tapers toward the projection 28, as shown in Figs. 3 and 5, thus correspondingly decreasing the area of the edge-turning wall 9^x toward its point of delivery. Inasmuch as the overhanging flange 18 of the primary 80 folding member lies slightly above the plane of guide-plate 19 while the lower portion of said primary folding member follows the taper of base member 9, it will be noted that the area of the hem cavity decreases toward 85 the delivery end of the attachment.

Further, it will be noted that the guide-wall 9^x is disposed mainly between the levels of the upper and lower limiting planes of the upwardly turned guide-wall 14^x. The inner 95 edge of the folded-over portion of material will thus be turned inwardly between said folded over portion and the main body portion of the work to form the hem.

When the hem fold is completed, a result 100 accomplished at or shortly before the time the initial stitch of the seam reaches the guide-plate 19, retraction of guide-plate 19 will expose the hem cavity and permit the initially stitched portion of the hem to 105 pass through the hemmer to the needles, whereupon the work may be withdrawn from the attachment, as will be understood without further explanation.

While the drawings show the preferred 110 embodiment of my invention it is to be understood that I do not wish to be limited to the specific construction therein illustrated. It is obvious that the gist of my invention lies in providing a hemmer with a 115 readily retractable lip or guide-plate such as that shown at 19 which enables circular hems to be completed without stopping the stitching mechanism, it being of course immaterial to what the lip is connected, or how 120 the lip is mounted for retractive movement or whether it be movable alone or with other part or parts of the machine so long as the lip is capable of being withdrawn to one side of the stitching line out of the way of 125 the initially formed stitches when a circular hem is nearing completion.

Having thus set forth the nature of the invention, what I claim herein is:

1. In a hemmer, a base member provided 130

with an edge-turning wall, a primary folding member carried by said base-member and formed with an upwardly turned guide-wall provided with an overhanging flange 5 on the side thereof toward said edge-turning wall and forming therewith a hem-cavity open at the top, and a retractible guide-plate mounted upon said base member with a free edge normally over- 10 hanging the edge-turning wall thereof and directed oppositely to said flange and disposed at the upper side of the hem-cavity.

2. In a hemmer, a base-member provided with an edge-turning wall, a primary folding member carried by said base-member and formed with an upwardly turned guide-wall provided with an overhanging flange 15 on the side thereof toward said edge-turning wall, a retractible guide-plate mounted upon said base-member with a free edge spaced 20 from that of said flange of the primary member and adapted for movement toward and from said flange and forming with said base- and primary-members a hem-cavity 25 open at the top, and a spring-detent for maintaining said guide-plate in operative relation with said base-member and primary folding member.

3. In a hemmer comprising a base member formed with a channel in its upper face, 30 a primary folding member adjustably connected to said base member and forming therewith a hem cavity, a guide-plate overhanging said hem cavity and provided with a grooved block adapted to slide within the 35 channel of said base member, and means for detaining the block within said channel.

4. In a hemmer comprising a base member formed with a channel in its upper face and 40 with an edge-turning wall, a primary folding member adjustably connected to said base member and forming therewith a hem cavity, a guide-plate normally overhanging said hem cavity and provided with a 45 grooved block adapted to slide within the channel of the base member, and a spring-pressed detent-pin mounted within the latter and adapted to enter the groove of said block.

5. The combination with a sewing machine cylinder-arm, of a hemmer carried by said arm and comprising a base member formed with a projecting edge-turning wall overlying said arm, a primary folding member 55 adjustably connected to the base member and forming therewith a hem cavity, a projecting U-shaped guide tongue carried by said folding member and opposed to said edge-turning wall, and a retractible guide-plate connected to said base member and 60 normally overlying the hem cavity.

6. In combination with stitch-forming mechanism, a hemmer having a hem-folding cavity defined by an upwardly turned fold- 65 ing wall terminating in an overhanging

flange and adapted to form the outer fold of the hem, an oppositely arranged folding wall and a lip overhanging said last-mentioned wall, said last-mentioned wall being disposed mainly between the levels of the 70 upper and lower limiting planes of the first-mentioned folding wall and adapted to fold in the inner edge of the folded over portion of the hem, said lip being lower than said overhanging flange and retractible, whereby 75 a circular hem may be completed without stopping the stitch-forming mechanism.

7. In combination with a stitching mechanism having a needle, a hemmer for turning under the edge of the fabric preparatory to 80 stitching, said hemmer comprising a primary folding portion having an upwardly turned guide-wall terminating in an overhanging flange and located at one side of the line of stitching, a complementary folding 85 portion over which a fabric is adapted to be passed said last named portion including a lip extending across the line of stitching toward but terminating short of said primary folding member, and means whereby said lip may be retracted away from said flange beyond and on the opposite side of the line 90 of stitching for enabling a circular hem to be completed without stopping the machine. 95

8. In a hemmer adapted for use with stitching mechanism, a primary folding member consisting of an upwardly turned concave wall terminating in an overhanging flange, a secondary folding member consisting of a wall facing the primary wall and a lip overhanging the secondary wall, said walls flange and lip defining a hem-cavity for hemming under the edge of a fabric, 100 said lip being mounted for retractive movement horizontally in order to permit the completion of a circular hem without stopping the stitching mechanism.

9. In combination with a stitch-forming mechanism a hemmer for hemming under 110 the edge of a fabric and having a hem forming cavity, a laterally retractable lip over which a fabric is adapted to pass and under which it is folded for enabling circular hems to be completed without stopping the stitch-forming mechanism. 115

10. In a hemmer, a body member having a hem-cavity and a slideway, a second member mounted to slide along said slideway and including a lip defining a portion of said 120 hem-cavity when said lip is in normal operative position, and means on said lip whereby it may be retracted from operative position automatically by the initial stitches in completing a circular hem. 125

11. In a hemmer having a hem-cavity a lip defining a portion of said hem-cavity and means including a spring for yieldingly holding said lip in operative position, the force of said spring being overcome by a 130

- retractive movement of the lip permitting the uninterrupted completion of a circular hem.
12. In a hemmer, a body member having a hem-cavity and a slideway, a second member mounted to slide along said slideway and including a lip defining a portion of said hem-cavity when said lip is in normal operative position, and means including an inclined edge on said lip whereby the lip may be retracted by the initial stitches in completing a circular hem.
13. In combination with a sewing machine having stitch-forming mechanism including a needle, a hemmer including a primary or outer folding portion having a concave upwardly extending guide-wall terminating in an overhanging flange, a complementary or inner folding portion over which a fabric is adapted to pass having a concave upwardly extending wall facing the upwardly extending wall of the primary or outer folding portion and also having an overhanging lip, the concave upwardly extending wall of the inner folding portion being wholly disposed between the horizontal planes of the upper and lower limits of the concave upwardly extending guide-wall of the outer folding portion, said lip being located in a plane below the overhanging flange and being also spaced from said flange, means permitting movement of the lip toward and from said overhanging flange, and a stop comprising a relatively fixed abutment and a projection fixedly connected with the lip for limiting the movement of the lip toward the flange of the outer folding portion.
14. In a hemmer for turning under the edge of a tubular article preparatory to stitching, in combination, an adjustable outer section having a concave upwardly extending wall terminating in an overhanging flange, a similar oppositely disposed inner section having an overhanging lip arranged at a lower elevation than said overhanging flange and spaced therefrom to form a fabric receiving channel communicating with a hem cavity located below the lip and flange, and means permitting movement of said lip bodily in a right line only toward and away from said flange including a tongue and groove connection.
15. A sewing machine having stitch-forming mechanism including a needle in combination with a fabric guiding attachment having relatively movable parts one of which is located in front of the needle and obstructs the complete stitching of an endless seam and is adapted to be shifted automatically to an ineffective position by the initial stitches of an endless seam.
16. In a hemmer having a hem-folding cavity, a lip defining a portion of said cavity, and means permitting said lip to be automatically displaced to an ineffective position at one side of the cavity by the initial stitches of a circular hem.
17. In a sewing machine, stitch-forming mechanism, in combination with a hemmer for guiding and folding tubular or endless work in its passage to the stitch-forming mechanism, said hemmer having relatively movable portions one of which normally obstructs the complete stitching of an endless hem and may be shifted to an unobstructing position allowing complete stitching of the endless hem through the action of the initial stitches securing the folded material in hem-form.
18. In a sewing machine, stitch-forming mechanism including a needle, in combination with a hemmer having at least one work-controlling member located normally in obstructing position directly in advance of the needle, and means permitting displacement of said work-controlling member in an ineffective position through the action of the initial stitches, whereby endless hems may be stitched completely without stopping the machine and without requiring the operator to manually shift said member.
19. In a sewing machine, stitch-forming mechanism including a needle, in combination with a fabric folding and guiding attachment having at least one active work-controlling element normally occupying a position obstructing complete stitching of endless or tubular articles and in front of the needle, and yielding means for maintaining said element in its normal obstructing position, said yielding means being arranged to permit the initial stitches of an endless hem to govern the movement of said active controlling element to a position not obstructing the complete stitching of an endless hem.
20. In combination with a sewing machine having stitch-forming mechanism including a needle and a cloth-plate, a hemmer having relatively movable sections one of which is in front of the needle and across the line of seam-formation in an obstructing position and is also retractile from its stitch obstructing position, while the other section is relatively fixed and is provided with means for directing the inner edge of the hem after the movable section is shifted from its stitch obstructing position on endless work.
21. In combination with a sewing machine having stitch-forming mechanism including a needle, an under hemmer having a relatively fixed section, a movable section in front of the needle across the line of seam-formation partly embraced by the fixed section and movable relative thereto, means on the fixed section substantially in front of the needle determining the width of the hem and guiding the inner edge of

the hem a uniform distance to one side of the needle, whereby shifting of the movable section to permit uninterrupted stitching of an endless hem will not alter the distance stitches are laid within the inner edge fold of the hem.

22. In a machine for sewing endless hems, the combination with stitch-forming mechanism including a needle, and feeding mechanism, of a hemmer having a hem-cavity bounded by an outer curved guide-wall for turning and guiding the outer edge-fold of a hem and an inner guide-wall facing said outer guide-wall and disposed between the levels of the upper and lower limiting planes of the outer guide-wall, a lip extending from the inner guide-wall toward the outer guide-wall and having a front edge extending across the line of seam-formation at the receiving end of the hemmer and an inner free edge extending lengthwise of the hem-cavity, said lip serving to fold in the inner or raw edge portion of the hem-fold and separate the hem-fold from the main body of the material being hemmed, said lip being mounted for displacement of its front and inner free edges away from the outer guide-wall and across the line of seam-formation to a position removed from the hem-cavity to permit the initially stitched portion of an endless hem to pass through the hemmer without distortion.
23. In a machine for sewing endless hems, the combination with stitch-forming mechanism including a needle, and feeding mechanism, of a hemmer including a base member and having a hem-cavity bounded by an outer curved guide-wall for turning and guiding the outer edge-fold of a hem and an inner guide-wall facing said outer guide-wall and disposed between the levels of the upper and lower limiting planes of the outer guide-wall, said guide-walls being

rigidly related to one another and to the base member, a lip adjoining said inner guide-wall and extending toward the outer guide-wall so as to fold in the inner or raw edge portion of the hem-fold and separate the hem-fold from the main body of the material being hemmed, said lip being shiftable relative to said rigidly related guide-walls and base member from its position between the hem-fold and the main body of the material to permit the initial stitches of an endless hem to pass through the hemmer to the needle.

24. In a machine for sewing endless hems, the combination with stitch-forming mechanism including a needle, and feeding mechanism, of a hemmer body having a hem-cavity bounded by an outer curved guide-wall for turning and guiding the outer edge-fold of a hem and an inner guide-wall facing said outer guide-wall and disposed between the levels of the upper and lower limiting planes of the outer guide-wall, a shiftable lip having a bearing contact with the hemmer body externally of the space embraced between said walls and extending from the inner guide-wall across the line of seam-formation toward the outer guide-wall so as to fold in the inner or raw edge portion of the hem-fold and separate the hem-fold from the main body of the material being hemmed, said lip having a range of movement on the hemmer body sufficient to permit its displacement to a position removed from the hem-cavity and the line of seam-formation.

In testimony whereof, I have signed my name to this specification, in the presence of two subscribing witnesses.

ALBERT H. DE VOE.
